UNITED STATES PATENT OFFICE

157,143

SPRAY DEVICE

Stanton F. Graham, Chicago, Ill.

Application September 21, 1949, Serial No. 5,114

Term of patent 3½ years

(Cl. D62—2)

To all whom it may concern:

Be it known that I, Stanton F. Graham, a citizen of the United States, residing at 740 West Adams Street, Chicago, Illinois, have invented a new, original, and ornamental Design for Spray Device, of which the following is a specification, reference being had to the accompanying drawing, forming a part thereof.

Figure 1 is a top plan view of a spray device embodying the present design;

Figure 2 is a fragmentary side view thereof;

Figure 3 is a front view thereof; and

Figure 4 is a fragmentary elevational view looking at the left of the sprayer head shown in Fig. 2, on a slightly reduced scale.

The dominant features of my design reside in the portions shown in full lines.

I claim:

The ornamental design for a spray device, substantially as shown and described.

STANTON F. GRAHAM.
